DETECTION SYSTEM

The invention described herein was made in the performance of work under a NASA contract and is subject to the provisions of Section 305 of the National Aeronautics and Space Act of 1958, Public Law 85-568 (72 Stat. 435; 42 U.S.C. 2457).

The present invention relates to a light-detection system and more particularly to a detection system which must detect a signal under low light level conditions for beam tracking, television camera, etc.

In the R. P. Borkowski et al. U.S. Pat. application Ser. No. 675,231, now U.S. Pat. No. 3,514,609 mention was made of the current-multiplication effect resulting from the coincidence of two beams of light on opposite sides of a cell. The present invention concerns a somewhat analogous effect, termed herein the photovoltaic enhancement effect. Generally speaking, the photovoltaic enhancement effect is obtained by illuminating coincident spots on a semiconductor by appropriate radiation while the semiconductor is operated in a photovoltaic mode.

One of the disadvantages of using semiconductors in the coincident beam current-multiplication-type of application is the slow rise and decay time of the semiconductor. In the present invention, use is made of the enhancement effect previously detected in photoconductors by operating semiconductors in the photovoltaic mode and use is made of advantages that this latter mode has over the former.

Among the features of the present invention are, first of all the identification of the existence of the photovoltaic enhancement effect. Secondly, there is a fast rise and decay time for low light levels, e.g. comparable signals give orders of magnitude slower response for the semiconductor operated with measurable bias voltages in the photoconductive mode. Third, the exhibition of an enhancement effect for fast chopping.

Briefly stated, the present invention contemplates the detection of a signal by using a photosensitive element with dual side electrodes transparent to selective radiation; amplifier means connected to the photosensitive element and signal utilization means connected to the amplifier. The photosensitive element is aligned so that one side of the photosensitive element can receive the signal thereon as a light beam spot. Scanning means are provided for scanning the other side of the photosensitive element with a light beam spot. The coincidence of said spots on opposite sides of said photosensitive element causes a detectable photovoltaic effect which is amplified by the amplifier so as to be used by the utilization means. The photosensitive element operates in the absence of any electrical excitation applied thereto.

The invention as well as the objects and advantages thereof will be more apparent from the following detailed description taken together with the accompanying drawing in which:

FIG. 1 is a schematic illustration of a semiconductor useful for the purposes of the present invention;

FIG. 2 shows in block diagram how the present inventive concept can be used for human voice transmission; and,

FIG. 3 depicts a block diagram of a low light level television camera.

In the present invention, use is made of a cadmium sulfide cell plate 4 shown in FIG. 1, having a thin metallic film 6, (Au for example), on one side of the cell and a counter electrode 8, such as NESA-conducting glass SnO_2 , on the other side. A signal is provided as a light spot on one electrode, while a detecting scanning spot scans the opposite side of the plate cell. The metal film of gold 6, and the cell plate of cadmium sulfide 4, together form a nonohmic photovoltaic junction therebetween because the work function of the gold film 6 is greater than the work function of the cadmium sulfide cell plate 4. The nonohmic junction is necessary when using only two aligned light spots for generating the voltage.

At the outset, it is necessary to explain what is meant by the term "photovoltaic enhancement effect." This is a voltage enhancement which results when small illuminated spots on opposite sides of a photosensitive cell are brought into spatial

opposition, with no applied electric field. If the photovoltages obtained by illuminating with either spot alone are V_R and V_L and the photovoltage obtained (at the same field) by simultaneous illumination is $V_{R,L}$, it develops that an enhancement effect is produced which is considerably greater than the sum of the individual voltages, e.g. $M = V_{R,L}/V_R + V_L > 1$. Note that $V_{R,L}$ does not necessarily imply large voltages since V_R and V_L individually may be small. Therefore large M -values are not dependent on large voltages. Herein, the letter M is used to indicate this enhancement effect and M -values as high as 25 for the photovoltaic mode have been detected. At green light intensities which create about 2 millivolts across the cell, the rise and decay times for photovoltage across a 75μ cadmium sulfide layer are at least 20 times shorter than are the photocurrent rise and decay times, the latter being measured under the same ambient conditions of illumination.

Although the photovoltaic effect is less than the photoconductive contributions, the higher blue-green frequencies disclose interesting situations. With a cell connected across a Tektronic 545 oscilloscope having 1 megohm internal resistance a photovoltaic enhancement is observed. The voltage amplitude in millivolts for advantageous spectral regions is given in table I.

TABLE I

30	Millivolts				Spot location
	$\lambda 450 \text{ m}\mu$	$\lambda 500 \text{ m}\mu$	$\lambda 633 \text{ m}\mu$	$\lambda 730 \text{ m}\mu$	
	0.1	0.2	0.5	0.9	NESA glass side of Cds cell.
	0.1	0.1	0.3	0.3	Evaporated electrode side of Cds cell.
35	5.0	2.0	1.0	2.0	Both sides of Cds cell.

It is seen that beams on both sides cause a 25 $\times$ increase in voltage for the shortest wavelength case, at the illumination level used, which was about 0.2 μw . through a pinhole mask of 0.4 mm. diameter.

The rise and decay times are significant since they are much faster than those obtained for the photoconductive case at the same level of illumination as shown in table II.

TABLE II

50	Photovoltaic (both sides illuminated)			Photoconductive (1 v. bias, both sides illuminated)	
	$\lambda 450 \text{ m}\mu$	$\lambda 500 \text{ m}\mu$	$\lambda 633 \text{ m}\mu$	$\lambda 500 \text{ m}\mu$	$\lambda 633 \text{ m}\mu$
	Rise, sec....	$\tau = 0.3$	≈ 0.1	< 0.1	≈ 2.0
55	Decay, sec....	$\tau = 0.002$	≈ 0.002	< 0.1	≈ 0.1

The decay times for the photovoltaic cases are actually faster than 0.002 sec, which is the reaction time of the optical shutter used in the experiment to stop and start the illumination.

An experiment was conducted which established that even at a 3,300 c.p.s. chopping rate, the mechanical limitation of a laboratory slotted disc, a large photovoltaic enhancement was detected. This finding was confirmed by the operation of the voice communication system (ibid, examples) where high-frequency audio components were transmitted.

An experiment to check on the spatial characteristics of the photovoltaic effect showed that the photovoltaic enhancement drops to $M=1$ the classical instance where the voltages become additive for the case when the illuminated pinholes in the masks over the CdS surfaces are not opposite one another.

The following examples are given to provide those skilled in the art a better appreciation of the invention.

EXAMPLE I (FIG. 2) — VOICE COMMUNICATION

The greater bandwidth which is obtained in the photovoltaic enhancement effect has been illustrated by the successful operation of a voice-modulated communications system. The human voice 40 was transmitted over a blue-green light beam 42 using a CdS detector 44 operated in the photovoltaic mode. A light spot 46 of constant intensity was projected by projection means 47 on one side 48 of the detector 44, a second spot of light 50 was modulated by a vibrating pinhole 52 attached to a transducer 54 which was driven by a microphone and amplifier. The second light spot 50 was projected by optics 56. The speaker contained a blue-green light source 53. The interruptions of this second beam produced photovoltaic enhancement, the output of which was fed into a second amplifier 58 and loud speaker system 60. The total energy of the two light beams was about 10^{-7} watts.

EXAMPLE II (FIG. 3) — LOW LIGHT LEVEL TELEVISION CAMERA

A second application of the photovoltaic enhancement effect was demonstrated for a low light-level television-camera system. An object 10 consisting of three asymmetric holes 12 in a piece of black paper was imaged by a lens system 14 on one side 16 of the CdS detector 18. A rectangular raster scan of green light 20 was projected on the opposite side 22 by a scan generator 24, the field of scan was about 1 cm. $\times$ 1 cm. When the scanning light was coincident with the hole pattern, an enhanced electrical signal was produced. The output of the detector 18 was amplified in an amplifier 26 and the modulation of the electron beam varied the intensity of the phosphor spot of an oscilloscope 28. The beam from this oscilloscope was synchronized by a feedback line 30 with the raster scan of the light beam from the scan generator 24. A true image of the object was observed on this oscilloscope.

We claim:

1. A signal-detector system comprising in combination:

a photosensitive element comprising a cell plate sandwiched between first and second radiation-transmitting electrodes, said first electrode being a film of metal bonded to said cell plate, the metal of said film and the material of said cell plate being selected so as to form a nonohmic photovoltaic junction therebetween, said film and said cell plate having respective work functions, said film work function being greater than said cell plate work function for generating a voltage when actuated; amplifier means connected to the element; utilization means connected to the amplifier; first input means adapted to project a signal on said photosensitive element as a light beam spot; and actuating means for applying a light beam spot to the other side of said element for actuating said element.

2. A signal-detector system according to claim 1 for use as a television-camera system,

wherein said cell plate is composed of cadmium sulfide and said first electrode is composed of gold;

wherein said actuating means includes:

scanning means disposed to provide a second light beam spot on the other side of said element for scanning said other side, said scanning means being adapted to provide a defined time interval when said second light beam spot coincides with said first light beam spot, said defined time interval being substantially greater than the response time interval of said photosensitive element; and

wherein said utilization means includes:

an oscilloscope connected to said amplifier means to display said output signal visually; and

a feedback line from said oscilloscope to said scanning means to synchronize the oscilloscope display with the scanning beam.

3. A signal-detector system according to claim 2, wherein

35 said scanning means includes a scan generator for projecting a raster scan of green light on the other side of said element.
